UNITED STATES PATENT OFFICE.

WILFRID JEAN, OF LOWELL, MASSACHUSETTS.

VALVE.

1,398,432.

Specification of Letters Patent. Patented Nov. 29, 1921.

Original application filed July 21, 1919, Serial No. 312,190. Divided and this application filed April 23, 1920. Serial No. 376,113.

To all whom it may concern:

Be it known that I, WILFRID JEAN, a citizen of the United States, residing at Lowell, in the county of Middlesex and State of Massachusetts, have invented certain new and useful Improvements in Valves; and I do declare the following to be a full, clear, and exact description of the invention, such as will enable others skilled in the art to 10 which it appertains to make and use the same.

My invention has for its object to provide an extremely simple and inexpensive, yet an efficient, reliable and easily operated 15 valve which may well be used on the heating systems of automobiles for directing the exhaust gases from the engine either to the usual exhaust pipe and muffler, or to branch piping leading to a heater.

With this object in view, the invention resides in the novel construction hereinafter described and claimed, the descriptive matter being supplemented by the accompanying 20 drawings.

Figure 1 is a top plan view of a valve constructed in accordance with my invention.

Fig. 2 is a side elevation.

Figs. 3 and 4 are respectively vertical and 30 horizontal sections on the planes indicated by the lines 3—3 and 4—4.

The present application is divisional of my pending U. S. application, Serial No. 312190, filed July 21, 1919, which application is devoted to a heating system in which the subject matter of the present case is embodied.

In the drawings accompanying this description the numeral 24 designates a cast 40 metal valve casing having a circular plug socket 25 whose upper end is closed by a removable plate 26 carrying a stuffing box 27 and a pair of vertical posts 28 upon which a segmental rack 29 is mounted, the three 45 parts 26, 28 and 29 being preferably cast of a single piece and secured to the casing 24 by screws 30.

The casing 24 is provided with two opposed nipples 31 flanged at 32 for attachment to the exhaust manifold, a portion of 50 which is indicated at 3, and such casing is equipped also with a third flanged nipple 33 to which a two-way coupling 34 is attached. Pipes 5 and 5^a lead from the two 55 openings in the couplings 34 to the heaters

when two of the latter are used, but when only one heater is employed, but one opening of the coupling 34 is necessary, and the other may be closed by an appropriate plug not shown.

A cylindrical valve plug 35 is received rotatably in the plug socket 25 and is provided with a transverse passage 36. This passage permits all of the exhaust gases to pass through the manifold 3, allows all of 65 said gases to travel through the heater or heaters, or permits a division of the gases so that they pass partly into the heaters and partly through the manifold. Stops 37 on the upper end of the plug 35, and another 70 stop 38 on the lower side of the cover plate 26, serve to limit the turning movement of the plug 35, and I provide means on the stem 39 for holding it in any position to which it may be set. This holding means 75 by preference consists of a crank-arm 40 carried by the stem 39 and a spring pressed pin 41 mounted on said arm and engaging with the rack 29. Any suitable handle may be employed for turning the stem 39 to set 80 the valve in the desired position.

By the use of the device, the exhaust gases may be so accurately controlled, that the heaters or heaters are made to raise the temperature of the automobile to practically 85 any desired degree.

The simple and inexpensive construction of the device renders it advantageous to manufacture and market, yet such device is highly efficient and durable and desirable in 90 every way. Since probably the best results may be obtained from the details disclosed, such details may well be followed, but within the scope of the invention as claimed, numerous minor changes may well be made. 95

I claim:

A valve of the class described comprising a substantially cylindrical vertical casing having a plug valve socket in its upper side, an inlet into said socket, and an outlet from 100 said socket, a valve plug having a passage for controlling communication between said inlet and said outlet, a removable cover plate for said plug socket secured to the upper side of said casing, a stem rising from 105 said plug to a point above said cover plate, a pair of posts rising from said cover plate at points spaced outwardly from said stem, an arcuate segment supported horizontally by said posts in concentric relation with said 110

stem, the upper side of said segment being provided with spaced teeth, a handle extending laterally from said stem over said segment and a spring-depressed pin slidably carried by the outer end of said handle 5 ably carried by the outer end of said handle and engaging the teeth of said segment to hold the stem and plug in adjusted position, the upper end of said pin having a knob adapted to be raised to release the pin and to then serve as means to swing said handle to operate the valve stem. In testimony whereof I have hereunto set and engaging the teeth of said segment to my hand. hold the stem and plug in adjusted position, WILFRID JEAN.
